Primary Examiner — Cathron C Brooks*Assistant Examiner* — Christian P. McLean(74) *Attorney, Agent, or Firm* — Nixon & Vanderhye P.C.(57) **CLAIM**

The ornamental design for a bottle dome, as shown and described.

DESCRIPTION

FIG. 1 is a rear perspective view of a bottle dome showing our new design;

FIG. 2 is a left side view thereof;

FIG. 3 is a right side view thereof;

FIG. 4 is a rear view thereof;

FIG. 5 is a front view thereof; and,

FIG. 6 is a top view thereof.

The broken lines illustrate portions of the bottle dome that form no part of the claimed design.
